UNITED STATES PATENT OFFICE

EDWARD BRUNHOFF, OF WYOMING, OHIO, ASSIGNOR TO THE ARNOLD ELECTRIC COMPANY, OF RACINE, WISCONSIN, A CORPORATION OF WISCONSIN

DISPENSING APPARATUS

Application filed December 15, 1928. Serial No. 326,325.

My invention relates to improvements in dispensing apparatus. One of its objects is to provide improved apparatus to reliably dispense malted milk and similar substances in powdered form. Another object is to provide improved apparatus adapted to reliably dispense substances having an affinity for moisture and hence tending to become moist and to adhere to operative parts of the apparatus and to obstruct the ports and passages thereof. Another object is to provide improved apparatus adapted to be conveniently separated into its components and then immersed in hot water to free the parts from any substances adhering thereto, and thereafter reassembled in operative relations. Another object is to provide improved means to regulate and control the movement of the dispensing apparatus to a forward step by 20 step movement of uniform proportions irrespective of the amount of manual energy imparted from time to time to actuate the dispensing apparatus. Another object is to provide an improved arrangement of exit port 25 gate actuated from and with the actuating mechanism and operating in connection with a separable dispensing hopper and dispensing apparatus whereby the separation and cleaning of the gate and dispensing apparatus is 30 facilitated. Another object is to provide an improved combined vertically reciprocating actuating lever and horizontally movable actuating means adapted to reduce to a minimum any tendency to upset the apparatus 35 through pressure applied to actuate the same.

My invention also comprises certain details of form and arrangement and combination of components all of which will be fully set forth in the description of the accompanying drawings, in which:

Fig. 1 is a front elevation of my improved apparatus.

Fig. 2 is a top perspective view of an exit gate detached.

Fig. 3 is a bottom perspective view of the gate shown in Fig. 2.

Fig. 4 is a plan of the dispensing apparatus shown in Fig. 1 with the hopper detached.

Fig. 5 is a perspective view of the dispensing spider detached.

Fig. 6 is a perspective view of the coupling key or spindle and agitating arms carried thereby detached.

Fig. 7 is a perspective view of a detachable cover plate detached.

Fig. 8 is a vertical sectional detail through the dispensing apparatus and actuating mechanism taken on line 8—8 of Fig. 4.

Fig. 9 is a plan of the actuating mechanism of Fig. 8 with the dispensing apparatus and gate detached therefrom.

Fig. 10 is a top plan of the detachable dispensing tray detached.

Fig. 11 is a bottom plan of the tray shown in Fig. 10.

Fig. 12 is a perspective view of the gate actuating lever detached.

Fig. 13 is a detail perspective view of a portion of the actuating mechanism.

Fig. 14 is a perspective view of another portion of the actuating mechanism detached.

Fig. 15 is a perspective view of the actuating mechanism ratchet wheel detached.

The accompanying drawings illustrate one embodiment of my invention, in which 15 represents a hopper which is seated detachably upon an annular ledge 16 of a metal dispensing tray 17, and held in place thereon by an external annular ledge 18. The hopper is preferably a section of transparent glass cylinder adapted to support a quantity of the powdered substance to be dispensed and expose the same to view while at the same time protecting the powder from exposure to the atmosphere to any considerable extent.

A lid or cap 19 closes the top of the hopper and the tray 17 closes the hopper at the bottom with the exception of an exit port 20 through the bottom of the tray 17, which is especially closed by means of a sliding gate 22, except when it is desired to dispense a measured portion of the powder through the exit port 20, when said port is opened by a transverse movement of the gate 22. The powder in the tray and hopper is thus protected against exposure to the atmosphere and is thus prevented from absorbing moisture from the atmosphere to any considerable extent.

The dispensing tray and the dispensing apparatus carried within said tray are detachably mounted upon a base member 24 by means of dowel pins 25 projecting downwardly from the under face of the tray 17 and entering into dowel recesses 26 formed in ears 27 projecting inwardly from the base member 24. The dispensing apparatus carried by the dispensing tray comprises a dispensing spider 27 having a central hub 28 and a series of radial arms 29, and a polygonal central perforation 30. A detachable plate 31 rests upon the upper face of the spider 27 being centered upon an annular shoulder 32 of the spider near the central perforation 30, and having a blade 38, the peripheral edge of which is let into a recess 33 in the ledge 16 so that the upper face of the plate 31 is substantially flush with said ledge 16, and serves to prevent the plate 31 from rotating relative to the tray 17 with the spider 27. A polygonal key or clutch stem 34 has a head 35 with a recess 36 to fit over the annular shoulder or extension 32 of the spider, so as to form a cap over said extension 32 and exclude powder from working beneath the cap or head 35 and into or through the recess 30 so as to reach the actuating mechanism located in the base 24. The cap 35 is provided with a series of radial arms 37 which move through the powder in the hopper above the plate 31 and serve to agitate the powder and insure the powder feeding uniformly into the spaces between the arms 29 of the spider. The ends of the arms 29 fit closely to the inner vertical walls of the dispensing tray 17 so as to automatically center the spider with reference to the tray. The tray 17 has an upwardly extending annular ledge 87 (see Fig. 8) which tends to prevent powder working beneath the spider toward the center of the bottom of the tray and thence into contact with the actuating mechanism located in the base 24. The stem 34, plate 31, spider 27 and gate 22 are readily separable from the dispensing tray 17, and said tray is readily separable from the hopper and from the base 24, in order to enable the members 34, 31, 27, 22 and 17 to be treated with hot water from time to time and quickly and thoroughly dried while heated and reassembled ready for operation. The tongue or blade 38 of the plate 31 is vertically above the exit port 20, to thereby prevent powder feeding directly and vertically from the hopper to the exit port. All the spaces or pockets between the radial arms 29 are open to receive powder from the hopper above said spider except the pocket 60 immediately beneath the blade 38. The radial arms 29 are tapered so that the pockets between said radial arms are slightly larger at the bottom than at the top, which facilitates detaching the powder from the pockets 65 successively as they reach a position above

the exit port 20. A downwardly extending lip 39 encircles the exit port 20 with extensions 40 leading therefrom which lip and extensions are surfaced to a single plane to enable the face of the gate 22 to make a close joint with said lip 39 and extensions 40. The extensions 40 serve as guides to hold the gate 22 in the same plane when the exit port is uncovered by the gate as when the gate covers the exit port, and they also serve to guide the gate back into position to cover the exit port. 70

The actuating mechanism is mounted in position with reference to the base member 24, so that the dispensing apparatus may be readily mounted upon and detached from the base member without disturbing the relation of the actuating mechanism and to enable the dispensing apparatus to be readily clutched to or coupled in operative relation to the actuating mechanism. The actuating mechanism comprises a ratchet wheel 42, which is journaled near opposite ends in central recesses 43 and 44 in plates 45 and 46 which are attached rigidly to ears 47 projecting inwardly at three substantially equidistant points from the inner face of the base member 24, by means of screws 48. The plates 45 and 46 are spaced apart, and the ratchet wheel 42 is held by shoulders 49 and 50 against movement axially. The hub of the ratchet wheel 42 has an axial polygonal recess 89 to receive and fit the polygonal stem 34, and thereby clutch the stem 34 and spider 27 operatively to said ratchet wheel. A rocker plate 51 is journaled upon the hub of the ratchet wheel below the ratchet teeth 52. A pawl 53 is pivotally mounted upon the rocker plate 51, and is actuated by a spring 54 to cause said pawl to engage the ratchet teeth 52 successively to drive the ratchet wheel forward step by step. A stop lug 55 carried by the plate 51 extends into the path of movement of the rear end of pawl 53 to limit the movement of said pawl relative to rocker plate 51. The rocker plate is also provided with a cam projection 56 and a cam finger 57. The rigid plate 45 is also provided with a cam finger 58, and has pivotally attached thereto a freely floating pawl 59, which pawl 59 is set in a reverse direction to that of the pawl 53. The pawl 59 is provided with a pin or cross bar 60 which projects from the top and from the bottom of the pawl 59. When the rocker plate 51 is rocked in clockwise direction the pawl 53 engages a tooth of the ratchet wheel 42 and rotates the ratchet wheel 42, the spider 27 and stem 34 a step forward equal to the distance from one ratchet tooth 52 to the next tooth, and at the same time the cam finger 57, which has moved clockwise, also engages the pin 60 of the pawl 59 and forces the free end of the pawl 59 toward the ratchet teeth until the free end of the pawl 59 engages a ratchet tooth 52 and blocks or stops further rotation of the ratchet 100

125

130

wheel. At the same time the cam projection 56, which is normally in position Fig. 9 to engage the pin 60 to hold the free end of the pawl out of engagement with the ratchet teeth 52, has moved clockwise away from the pin 60, thereby allowing the finger 57 to throw the pawl 59 inwardly. The stationary finger 58 engages the pin 60 to limit the outward movement of pawl 59. As soon as pawl 59 has blocked the movement of the ratchet wheel 42, the rocker plate 51, pawl 53, and cams 56 and 57 move the space from one ratchet tooth to the next ratchet tooth counterclockwise, which enables the pawl 53 to engage the next ratchet tooth, and causes the finger 57 to move away from the pin 60, and the projection 56 to engage the pin 60 and force pin 60 and pawl 59 outwardly until the free end of pawl 59 is out of the path of the ratchet teeth 52 and the pin 60 is in engagement with the finger 58. The rocker plate 51 is attached pivotally to one end of a link 62. The opposite end of the link 62 is pivotally attached to a manually operable lever 63, which is pivotally attached at 64 to the base member 24. A spring 91 normally holds the lever 63 in retracted position. Power is applied to a head or knob 65 of lever 63 by pressing vertically downward thereon, which downward pressure does not in any way tend to upset the base or the members mounted thereon, but instead tends to increase the stability of the base 24 while the apparatus is being actuated. A gate actuating lever 67 is pivotally mounted at 68 upon the hub of the ratchet wheel 42 while a tubular stud 69 fits over the end of the pin or stud 70 carried by the rocker plate 51, and upon which the pawl 53 pivots. Movement of the rocker plate 51 causes the free end of the gate lever 67 to sweep through the arc of a circle beneath the tray 17 and above the base member 24 which is recessed at 71 (see Fig. 1) to permit this lever 67 to extend outwardly from the base member 24 and to move relative thereto. The lever 67 is held in place relative to the ratchet wheel hub and the plates 45 and 46 of the base member by means of a thin triangular retaining plate 72 attached rigidly to and above the plate 45, with the lever 67 interposed. The free end of the lever enters between the side plates 73 and 74 of a channeled member attached to the lower face of the gate 22. The free end of the lever 67 also has a cross rib 75 which enters a slot 76 across the channeled member of the gate to retain the gate detachably in position upon the free end of the lever 67. The lever 67 being held firmly between plates 72 and 45 is enabled to act resiliently upwardly to press the gate 22 upwardly against the lip 39 and extensions 40, to provide a practically air tight joint to exclude moisture carrying air from the hopper interior.

65 The apparatus herein illustrated and de-

scribed is capable of considerable modification within the scope of the claims without departing from the spirit of my invention.

What I claim is:

1. Dispensing apparatus comprising a base member, actuating mechanism mounted in said base member, a manually operable actuating lever operable by pressure downwardly thereon in a substantially vertical direction, a dispensing tray separably mounted upon and above said base member and actuating mechanism and provided with a dispensing port, a central perforation and an annular raised powder excluding rib extending upwardly from the floor of said tray and encircling the central perforation thereof, a dispensing spider seated upon the floor of said dispensing tray outside of said powder excluding rib, a plate located above said dispensing port and above said dispensing spider and nonrotatable relative to said tray, and upwardly removable means for detachably coupling said spider with said actuating mechanism.

2. Dispensing apparatus comprising a base member, actuating mechanism mounted in said base member, a manually operable actuating lever, a horizontally reciprocating gate actuating lever operatively connected to said manually operable actuating lever, a dispensing tray separably mounted upon and above said base, and provided with a dispensing port through the bottom thereof, means located in said tray and operable through said manually operated actuating mechanism to dispense measured quantities of powder from said tray through said dispensing port, a gate resting loosely and removably upon said gate actuating lever and held yieldingly thereby in contact with the bottom of said dispensing tray and normally in position to close said dispensing port and operable periodically in unison with the movements of said actuating lever to uncover said dispensing port.

3. Dispensing apparatus comprising a base member, actuating mechanism mounted thereon having a vertically reciprocating manually operable actuating lever and a substantially horizontally oscillatable gate actuating lever, a dispensing tray having a dispensing port separably mounted upon said base above said actuating mechanism, dispensing means carried by said dispensing tray, means to couple said dispensing means to said actuating mechanism and a gate separable from said gate actuating lever interposed between said gate actuating lever and said dispensing port and normally closing said dispensing port.

4. Dispensing apparatus comprising a base member, a ratchet wheel journaled upon a vertical axis relative to said base member and rotatable step by step in one direction, a rocker plate journaled upon the hub of said

ratchet wheel and reciprocably movable thereon, a pawl carried by said rocker plate to engage and drive said ratchet wheel, a manually operable vertically oscillatable actuating lever operatively connected to said 5 rocker plate to reciprocate said plate, a gate actuating lever journaled upon the hub of said ratchet wheel and operatively connected to said rocker plate to reciprocate therewithin to a substantially horizontal direction, a dispensing tray mounted above said base and gate actuating lever having a dispensing port, dispensing apparatus located within said dispensing tray, a gate interposed between said dispensing tray and said gate lever and bearing resiliently upon the bottom of said dispensing tray to normally close said dispensing port, said gate being reciprocably operable to uncover said dispensing port.

20 In testimony whereof I have affixed my signature.

EDWARD BRUNHOFF.
